UNITED STATES PATENT OFFICE

JOHN THORNTON, OF YOUNGSTOWN, OHIO

FURNACE CONSTRUCTION

Application filed February 6, 1931. Serial No. 513,830.

This invention as indicated relates to a furnace construction, more particularly it comprises a construction especially adapted for use with the furnace charging openings of open hearth furnaces, but it is not to be limited to such use inasmuch as it is suitable for various types of industrial furnaces wherein it is desired to protect the wall and skewback of the furnace from the destructive effects of heat at the point of connection of the door frame with the furnace.

It has heretofore been the practice to place heavy door frames, preferably of hollow construction and provided with water circulation connections, at the charging opening of an open hearth or like industrial furnace, and to support fire resistant material such as silica brick on such frame in order to prevent leakage of gases about said structure. Such brick has only a limited length of service before deteriorating and frequent replacing of the same is necessary.

The present invention has for its principal object the provision of a furnace construction wherein the charging opening is provided with a frame which is suitably water cooled, said frame being formed with an extension so spaced from the wall structure of the furnace as to provide for a space which may be filled with a material very highly heat-resistant, and which will last almost indefinitely under very severe service. Another object of the invention is to provide a supporting means, for a plastic material highly heat-resistant in character, which will have a locking and positioning effect on the same and prevent its becoming displaced through vibration or shock such as occasionally is imparted to the door frame of a furnace by the charging apparatus. Other and further objects of the invention will appear in the course of the following description. To the accomplishment of the foregoing and related ends, said invention, then, consists of the means hereinafter fully described and particularly pointed out in the claims.

The annexed drawing and the following description set forth in detail certain mechanism embodying the invention, such dis-

of various mechanical forms in which the principle of the invention may be used.

In said annexed drawing:

Fig. 1 is a perspective view showing one form of furnace construction embodying the principles of the invention; Fig. 2 is a similar view showing a slightly modified form of construction.

As is clearly shown in the drawing, the furnace 1 comprises the usual side walls (not shown) and a roof structure 2, the roof structure being supported upon a channel skewback 3 having a flange 4 at its lower edge upon which the units forming the roof structure are supported. The furnace door frame 5 is positioned in front of said channel skewback, being supported chiefly by its own weight. The door frame as illustrated comprises two upright side frame members 5, the upper ends 6 of which preferably extend slightly above the lower edge of the skewback. At a point spaced from said upper ends and slightly below the lower edge of the skewback, a cross member 7 of the door frame is provided, said cross member having a rearward extension 8 which is adapted to enter the furnace proper. This rearward extension is made preferably as an integral part of the door frame and is adapted to receive the cooling water in its course of circulation through the door frame.

The cooling water is admitted to one side member of the door frame through a pipe 11 which preferably extends to a point adjacent its lower end. A similar pipe 12 is positioned in the other side member of the door frame and serves to receive the water circulated through the structure and carry it to a point of discharge. The extension on the door frame, as stated, is in a rearward direction entering within the interior of the furnace and is of such extent that it projects not only beyond the channel skewback, but beneath the refractory materials forming the roof structure supporting thereon.

The extension on the door frame preferably is inclined upwardly, as is shown more particularly in Fig. 2 of the drawing, and may be curved or given any desired configuration to engage throughout all or a portion of

its extent so as to provide a slight wedging action upon the packing material 13 of heat-resisting quality which is engaged above the same. This packing material, preferably 5 comprises chrome ore particles which withstand substantially twice the amount of heat as ordinary silica brick will withstand. When the door frame is placed in position, the space immediately above the extension 10 is filled with the chrome ore in plastic form which is rammed solidly into position not only beneath the lower edge of the skewback, but also beneath the forward portion of the roof structure or forward wall structure, 15 as the case may be, as has heretofore been indicated.

Other modes of applying the principle of my invention may be employed instead of the one explained, change being made as regards 20 the mechanism herein disclosed, provided the means stated by any of the following claims or the equivalent of such stated means be employed.

I therefore particularly point out and distinctly claim as my invention:

1. A furnace structure comprising a skewback support, an arched roof structure engaged upon said skewback, a hollow water-cooled frame for a furnace door beneath said 30 skewback, such frame comprising a pair of upright members and a connecting supporting member projecting upwardly and rearwardly in spaced relation beneath said skewback and its associated arch, said upright 35 members being positioned outwardly of the front wall of the furnace with their upright ends overlapping the forward face of said skewback, and a single layer of fire-resistant packing material interlockingly engaged in 40 the space between said arch and said rearwardly and upwardly inclined supporting member and behind adjacent structural elements and adapted to be forced while plastic 45 into said rearwardly decreasing space between said frame and said arch through wedging action when rammed thereinto from a point outside the front wall of said furnace.

2. A furnace structure comprising a skewback support, an arched roof structure engaged upon said skewback, a hollow water-cooled frame for a furnace door beneath said skewback, such frame comprising a pair of upright members and a connecting supporting member projecting upwardly and rearwardly in spaced relation beneath said skewback and its associated arch, said upright 55 members being positioned outwardly of the front wall of the furnace with their upright ends overlapping the forward face of said 60 skewback, and a single layer of fire-resistant packing material interlockingly engaged in the space between said arch and said rearwardly and upwardly inclined supporting member and behind the upright members and 65 adapted to be forced while plastic into said

rearwardly decreasing space between said frame and said arch through wedging action when rammed thereinto from a point outside the front wall of said furnace.

Signed by me this 15th day of November, 70
1930.

JOHN THORNTON.
